STOVE.

No. 16,935.

Patented Oct. 12, 1886.

*Fig. 4.**Fig. 3.**Fig. 5.*# UNITED STATES PATENT OFFICE.

JOHN F. MARTENS, OF CINCINNATI, OHIO, ASSIGNOR TO REDWAY & BURTON, OF SAME PLACE.

DESIGN FOR A STOVE.

SPECIFICATION forming part of Design No. 16,935, dated October 12, 1886.

Application filed March 15, 1886. Serial No. 195,360. Term of patent 3½ years.

To all whom it may concern:

Be it known that I, JOHN F. MARTENS, a citizen of the United States, and a resident of the city of Cincinnati, in the county of 5 Hamilton and State of Ohio, have invented and produced a new and original Design for Cylinder-Stoves, of which the following is a full, clear, and exact description, reference being had to the accompanying photographic 10 illustrations, forming part thereof.

Figure 1 of the photographs shows in perspective the front and the side of a stove embodying and illustrating my design. Fig. 2 shows the ornamentation of the plate attached to the rear of the stove. Fig. 3 shows the side of the stove in elevation. Fig. 4 is 15 a flat view of the cover. Fig. 5 illustrates the frame-work of the door.

The ornamentation of the band A is best 20 shown in Fig. 3, where the figure, which occurs three times on the band, is shown in full. This figure consists of a central heart-shaped piece reversed, from which there extends symmetrically on each side a gracefully curved 25 vine-stem, having delicate tendrils and conventional five-petaled flowers. This ornamentation is on a roughened background.

The ornamentation of the band B consists 30 of a series of similar U-shaped figures, equal to each other in size, and lying side by side.

The ornamentation of the plate C is laid 35 on a roughened background. It is made in two symmetrical lateral halves. From the heart-shaped figure 1 in the center of the lower part of the design there arises a stalk, 2, surmounted by a conventional flower, 7. From the stalk 2 on each side there curves upwardly and outwardly a branch, 3, which has a calyx, 8, just before its bifurcation. The 40 upper division of the branch 3 terminates in a trilobed leaf, 4, and the lower branch terminates in a four-lobed leaf, 5. Surrounding the stalk 2 at the point where the branches 3 are given off is a conventional calyx, 6. From 45 the upper part of the heart-shaped figure a branch, 9, curves downwardly and outwardly, and then upwardly, and terminates in a bunch of berries, 10, immediately below which is a cluster of leaves.

50 The ornamentation of the band D consists of a series of similar raised octagonal figures

having a central circular depression. There is a bead above and below this row of octagonal figures, and between the beads the background is stippled.

The ornamentation of the band E is somewhat similar to the ornamentation of the band A. A central heart-shaped figure has extending from each of its lower corners three branches, the first and third of which terminate in trilobed leaves, while the middle one is gracefully curved upon itself. A triangular space is separated from the main portion of the design by a curved bead, and in this space is a twig with a conventional trilobed 55 leaf. The background for the design of this band E is roughened.

The top of the stove is covered by a dome-shaped cover, H, which is itself surmounted by an urn. The ornamentation of this cover 70 H is well shown in Fig. 4. On a roughened background three separate sprays are displayed arranged around the center of the dome. These sprays differ slightly from each other in detail, but are very similar in general design, each consisting of a stalk carrying conventional leaves and flowers.

The plate K of the base of the stove is square in outline, with the corners cut off. Its edge is beveled. The lower plate, M, is 75 similar in shape to the plate K above.

The frame-work of the door N, which is intended to hold mica plates, is shown in Figs. 1 and 5. This frame-work consists of vertical and horizontal bars, arranged as shown, and 80 modified near the corners by scroll and fluted work, as shown.

What I claim as new, and desire to secure by Letters Patent, is—

1. In a design for a stove, the ornamentation 90 of the plate C, substantially as shown and described.

2. In a design for a stove, the ornamentation of the band D, substantially as shown and described.

3. In a design for a stove, the ornamentation 95 of the band E, substantially as shown and described.

4. In a design for a stove, the ornamentation of the fire-pot section, consisting of the somewhat similarly ornamented bands A and E and plate C, and the plain ornamentation of 100

the bands B and D, placed between the plate C and the bands A and E, substantially as shown and described.

5. In a design for a stove, the shape and ornamentation of the uru and dome H, combined as shown and described.

6. The stove design having as parts the ornamentation of the bands A, B, D, and E,

the ornamentation of the plate C, the ornamentation and configuration of the dome H, to and the configuration of the foot-rest F, as shown and described.

JOHN F. MARTENS.
